UNITED STATES PATENT OFFICE.

BERNHARD POEHLAND, OF WOODHAVEN, NEW YORK.

FASTENER FOR TAILPIECES OF MUSICAL INSTRUMENTS.

1,337,793.

Specification of Letters Patent. Patented Apr. 20, 1920.

Application filed October 2, 1919. Serial No. 328,062.

To all whom it may concern:

Be it known that I, BERNHARD POEHLAND, a citizen of the United States, residing in Woodhaven, in the county of Queens and State of New York, have invented certain new and useful Improvements in Fasteners for Tailpieces of Musical Instruments, of which the following is a specification.

My invention relates to a simple and effective fastener for tailpieces of musical instruments, which can be easily applied and removed, and avoid all necessity of the use of screws, cord, gut, etc.; and my invention consists of a suitable piece of wire formed at one end with hooks for holding the tailpiece, and the other end looped to attach to the end pin of the instrument.

In order that my invention may be fully understood, I will proceed to describe the same with reference to the accompanying drawings, in which—

Figure 1 is a perspective view of a violin with my fastener attached thereto. Fig. 2 is a top view of the fastener. Fig. 3 is a bottom view of the fastener applied to the tailpiece, and Fig. 4 is a detail view of a section on the line A—A of Fig. 3.

In the said drawings, 1 represents a violin; 2, the tailpiece thereof; 3, the fastener therefor, and 4 the end-pin over which the loop-end of the fastener fits. The fastener consists of wire or other suitable non-elastic material, formed as shown in drawings, and finished in any desired manner.

Fig. 2 shows enlarged top view of fastener, 5, 5, being portions bent upward and backward to form hooks for engaging holes which are found in all tailpieces of violins and like instruments. The loop end, 6, is spread outwardly to allow of placing over end pin 4, then narrowed at 7 to such width as will permit of even contact and strain on said end pin 4, also preventing the fastener from slipping off.

Fig. 3 shows an enlarged bottom view of my fastener with hooks 5, 5, engaged in the holes of tailpiece, 2.

Fig. 4 is a sectional view of tailpiece 2 on line A—A of Fig. 3, showing hook, 5, engaged in the hole of the tailpiece. 50

In use, the fastener is attached first to the holes of the tailpiece as shown, then slipped over the end pin 4, until the narrow part of loop, 7, rests securely; thereupon the fastener is bent over the edge of the instrument 55 until the tailpiece occupies the proper position in relation to the bridge and the neck, after which the strings are tightened, making the instrument ready for use.

Most violins and the like are equipped with 60 a tailpiece whereon the fastener consists of a twisted strand of gut, which is very liable to break under variable atmospheric conditions, causing considerable delay in replacement. My fastener will therefore also serve 65 as an excellent emergency appliance. It can be cheaply constructed, is very rapid of adjustment without any tools, and owing to metallic material, will not stretch. On the contrary, gut when newly used, continues to 70 stretch for many hours, necessitating frequent tuning of all the strings.

Having thus described my invention, and the reasons therefor, the following is what I claim as new and desire to secure by Letters 75 Patent:—

1. The combination of a musical instrument tailpiece having the usual two holes drilled therein, and a fastener for said tailpiece, said fastener being formed of wire 80 with hook ends engaging said holes, substantially as and for the purpose set forth.

2. As a new article of manufacture, a fastener for tailpieces of musical instruments, formed of wire with ends bent into 85 hook form, and the middle portion looped for engagement with the end pin of the instrument, substantially as shown and described.

BERNHARD POEHLAND.
